UNITED STATES PATENT OFFICE

2,028,823

CHAIR

Bernard George Bruening, Evansville, Ind.

Application August 22, 1935, Serial No. 37,395

1 Claim. (Cl. 155—1)

The invention relates to improvements in chairs of the type having front posts, relatively tall rear posts, rungs securing all of said posts in fixed relation with each other, a seat extending from the front posts to the rear posts, and slats or other back-forming means carried by the upper portions of said rear posts. Chairs of this general type, particularly ladder-back chairs are very easily tipped rearwardly, and it is the object of the present invention to provide a new and improved construction in which this is prevented by a pair of rearwardly declined skids which are secured to the lower portions of the front posts, said skids supporting the rear posts and projecting rearwardly a considerable distance therefrom.

With the foregoing in view, the invention resides in the novel subject matter hereinafter described and claimed, description being accomplished by reference to the accompanying drawing.

Figs. 1 and 2 are perspective views showing a ladder-back chair constructed in accordance with the invention.

A preferred construction has been shown and will be specifically described, with the understanding that within the scope of the invention as claimed, variations may be made.

The front posts of the chair are denoted at 3, the lower ends of said posts being adapted to rest upon a floor or the like. Projecting rearwardly from the lower portions of the posts 3 are two rearwardly declined skids 4, the front ends of said skids being secured at 5 to the posts 3 at points spaced upwardly from the lower ends of the latter. The rear ends 6 of these skids project considerably beyond the relatively tall back posts 7 of the chair and are adapted to rest

upon the floor or the like, coacting with the lower ends of the front posts 3 in forming a stable supporting base. The lower ends of the posts 7 are rigidly secured at 8 to the skids 4.

All of the posts 5 and 7 are held in rigid relation with each other by suitable rungs 9 and some of these rungs are preferably utilized to support a suitable seat 10 which extends from the front to the rear posts. The upper portions of the rear posts 7 carry slats 11 or other desired back-forming means.

By providing the novel construction shown and described, the chair is effectively braced against tilting rearwardly and moreover, its general rigidity is increased.

While the details disclosed may be followed if desired, attention is again invited to the possibility of making variations within the scope of the invention as claimed.

I claim:—

A chair comprising two front posts, two rearwardly declined skids projecting rearwardly from the lower portions of said front posts, the front ends of said skids being secured to said front posts at points spaced upwardly from the lower ends thereof, the rear ends of said skids and the lower ends of said front posts being adapted to rest upon a floor or the like, two relatively tall rear posts rising from the rear portions of said skids, said rear posts being secured to said skids at points spaced forwardly from the rear ends of said skids, rungs securing all of said posts in rigid relation with each other, a seat spaced above said skids and extending from said front posts to said rear posts, and back-forming means secured to the upper portions of said rear posts.

BERNARD GEORGE BRUENING.
